SHOE SHINING MACHINE

Otto M. Dyer, Jr., 1 Lafayette Plaisance, Apt. 1205,
Detroit 7, Mich.

Filed Feb. 16, 1961, Ser. No. 89,726
6 Claims. (Cl. 15—97)

This invention relates to polishing devices, and more particularly to a device for shining and polishing shoes.

Briefly, the invention comprises a foot rest for a shoe with two slotted upstanding guide tubes mounted on each side of the shoe support. Mounted slidably in each guide member is an elongated flexible spring having hooks thereon which extend through slots in the rigid guide members. The upper ends of the springs have handles fixed thereto and the hooks are connected by polishing rags extending over the shoe support. When the handles are manually reciprocated, the springs in turn reciprocate the hooks which move the polishing cloths back and forth for polishing the shoe.

Accordingly, it is a primary object of this invention to provide a shoe shiner that is so constructed that the operator thereof will be able to acquire a good shoe shine without bending or soiling his hands.

It is another object of the invention to provide a shoe shiner that may be operated with a minimum of effort and with maximum comfort.

It is another object of the invention to provide a shoe shiner device that is not only manually operated, but is also adapted to be operated by power means if so desired.

It is another object of the invention to provide a shoe shining device that is simple in design, economical to manufacture, and durable and reliable in use.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 shows a plan view of this invention;

FIGURE 2 shows a front elevational view of the invention.

FIGURE 3 is a side elevational view;

FIGURE 4 is an enlarged cross-sectional view taken substantially on the plane of line 4—4 of FIGURE 2;

FIGURE 5 is a cross-sectional view taken substantially on the plane of line 5—5 of FIGURE 4; and

FIGURE 6 is an enlarged view taken substantially on the plane of line 6—6 in FIGURE 1.

Referring to the drawings, it can be seen that the shoe shine device is mounted on a rectangular base board 10. Spaced several inches above the base board 10 and lying in a plane parallel thereto, is a foot rest 12 secured thereto by means of vertically extending spaced parallel legs 14 and 16. As shown in FIGURE 1, the board 12 for supporting the shoe 18 is shaped substantially like the sole of a shoe, however, the toe portion of the board is cut off so as to form a blunt end 20.

Secured to the base board 10 are two guide tubes 22 and 24. Each guide tube is substantially identical, and each comprises a vertically extending portion 26 connected to the end of a horizontally extending J-shaped portion 28. The other end of the J-shaped portion 28 is connected to a vertically extending portion 30 which is parallel to the portion 26, and the upper end of the vertically extending portion 30 is connected to a horizontally extending portion 32. All of the portions of each guide tube are formed integrally by bending one piece of tubular material such as stock metal tubing. For clarification, the various portions of the members 22 and 24 are given the same reference numerals, however, the reference numerals for the portion 24 have a prime added thereto.

2

The tubular guides 22 and 24 are mirror images of one another except for the fact that the rear portion 28 of the member 22 has a slight hump 34 formed therein so as to permit it to pass over the portion 28'.

5 The J-shaped portions 28 and 28' of the guide tubes are secured to the base board 10 by means of clamps 36, 36', 38 and 38'. Each of the clamps has an arcuate portion fitting over the top surface of the tubular guides and an integral flange formed therewith. Each flange has an aperture therein with a screw extending therethrough and into the base 10 for removably securing the clamps and guide tubes to the base board. As shown in FIGURES 1 and 2, the clamps 38 and 38' have a plurality of spaced arcuate recesses 40 and 40' formed therein. By loosening the clamps 38 and 38', the portions 28 and 28' may be selectively received in any one of the plurality of recesses 40 and 40' for adjusting the spacing between the guide tube so as to fit shoes of varying sizes.

20 Slidably fitting within each hollow guide tube is an elongated coil spring member 42. Each of the spring members 42 extend to the lower ends of the guide tubes and project from the upper end a substantial distance such as one foot. For stiffening the upper ends of the coil springs 42, a solid rod 44 is inserted therein and secured thereto. The solid rod members 44 extend almost to the lower ends of the vertical portions 26 when the springs are fully inserted into the guide tubes. Fixed to the upper ends of the springs 42 and stiffening rods 44 are 25 operating handles 46. The springs and rods extend a substantial distance into bores 48 in the lower central portion of the handles.

Each of the vertical portions 26 of the guide tubes has an elongated vertically extending slot 50 within its inner surface. The slots 50 extend from the base 10 to an inch or so above the shoe board 12. Slidably mounted within each slot 50 is a hook 52 which has a threaded shank 54 screwed through the spring 42 and into the stiffening rod 44.

30 The horizontally extending portions 32 of the guide tubes also have elongated slots 56 extending throughout the lengths of the portion 32. These slots 56 receive hooks 58 which are identical to the hooks 52. The threaded shanks of the hooks 58 extend into cylindrical blocks 60 which are secured to the ends of the spring members 42. To prevent the hooks 58 and blocks 60 from being ejected from the ends of the portions 32, radial pins or screws 62 may be inserted radially through the ends of the guide tubes as shown in FIGURE 6.

35 For polishing the rear or heel portion of the shoe 18, a polishing cloth 64 has its ends hooked onto the hooks 58, 58' and its middle portion loops around the rear portion of the shoe to be polished.

40 The central portion of the polishing cloth 64 may be supported by a tapered or tooth pick like flexible member 66 which has its lower end 68 secured within the rear end of the base 10 as shown in FIGURE 3. The upper end of the member 66 may be secured to the cloth 64 by any conventional means, such as inserting the upper pointed end of the member 66 into a hem or fold 45 in the polishing cloth.

45 A second elongated polishing cloth 70 has its opposite end portions connected to the hooks 52 and 52' as shown in FIGURES 3 and 2.

50 To operate the shoe polishing device, the shoe to be polished is placed on the shoe board 12 with the toe of the shoe extending beyond the blunt end 20 and beneath the polishing cloth 70. The back end of the shoe is pushed tightly against the polishing cloth 64 so that it snugly envelops the rear portion of the shoe. The operator then grasps the handle 46 in his left hand and the handle 46' in his right hand and alternately reciprocates the handles in opposite directions. This causes the 55

hooks 52 and 52' to reciprocate in opposite directions thereby moving the cloth 70 so as to polish the toe of the shoe, and it further causes the hooks 58 and 58' to reciprocate in a horizontal plane in opposite directions so as to move the cloth 64 back and forth over the rear portion of the shoe. The flexible member 66 being composed of a very resilient material such as rubber or flexible plastic, freely permits the cloth 64 to move back and forth over the rear of the shoe. Since the handles 46 and 46' normally extend about to a point just below the operator's waist, it can be seen that he can operate the shoe polishing device without stooping or bending and without soiling his hands or touching the shoes. This permits substantially the entire shoe to be polished in a very short time with a minimum of effort.

When the polishing cloths 70 and 64 become worn, they can be replaced very easily and rapidly.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A device for shining shoes comprising a support for a shoe, guide means fixed to said support on each side thereof, force transmitting means extending through each of said guide means and vertically upward, operating means connected to the upper ends of said force transmitting means, flexible polishing means connected to and between the lower ends of said force transmitting means, said force transmitting means being adapted to transmit tensile forces to said polishing means for keeping it taut and moving it over the shoe, said guide means comprising rigid elongated tubes and said force transmitting means comprising elongated flexible members, said tubes having vertically extending portions with vertically extending slots therein, a fastening means connected to each of said force transmitting means and extending through each of said slots in a manner so as to allow substantial relative movement between said force transmitting means, said polishing means including a first member connected to said fastening means and adapted to contact and polish the toe of said shoe.

2. A device as recited in claim 1 wherein said polishing means comprises a cloth.

3. A device for shining shoes comprising a support for a shoe, guide means fixed to said support on each side thereof, force transmitting means extending through each of said guide means and vertically upward, operating means connected to the upper ends of said force transmitting means, flexible polishing means connected to and between the lower ends of said force transmitting means,

said force transmitting means being adapted to transmit tensile forces to said polishing means for keeping it taut and moving it over the shoe, said guide means comprising rigid elongated tubes and said force transmitting means comprising elongated flexible members, the upper ends of said flexible members extending beyond said tubes, said ends being stiffened and connected to handles, said tubes having vertically extending portions with vertically extending slots therein, a fastening means connected to each of said force transmitting means and extending through each of said slots in a manner so as to allow substantial relative movement between said force transmitting means, said polishing means including a first member connected to said fastening means and adapted to contact and polish the toe of said shoe.

4. A device for shining shoes comprising a support for a shoe, guide means fixed to said support on each side thereof, force transmitting means extending through each of said guide means and vertically upward, operating means connected to the upper ends of said force transmitting means, flexible polishing means connected to and between the lower ends of said force transmitting means, said force transmitting means being adapted to transmit tensile forces to said polishing means for keeping it taut and moving it over the shoe, said guide means comprising rigid elongated tubes and said force transmitting means comprising elongated flexible members, said tubes having vertically extending portions with vertically extending slots therein, a fastening means connected to each of said force transmitting means and extending through each of said slots in a manner so as to allow substantial relative movement between said force transmitting means, said polishing means including a first member connected to said fastening means and adapted to contact and polish the toe of said shoe, said guide means comprising rigid elongated tubes and said force transmitting means comprising elongated flexible members, said tubes having vertically extending portions with vertically extending slots therein, a fastening means connected to each of said force transmitting means and extending through each of said slots in a manner so as to allow substantial relative movement between said force transmitting means, said polishing means including a first member connected to said fastening means and adapted to contact and polish the toe of said shoe.

5. A device as recited in claim 4 wherein the central portion of said second member is flexible and is supported by a generally resilient member.

6. A device as recited in claim 5 wherein said resilient member and shoe support are mounted on a base board.
